1
2,854,399REMOVAL OF HEAVY METALS FROM
PETROLEUM STOCKS

Sol W. Weller, Drexel Hill, Pa., assignor to Houdry Process Corporation, Wilmington, Del., a corporation of Delaware

No Drawing. Continuation of application Serial No. 267,307, January 19, 1952. This application September 21, 1954, Serial No. 457,569

3 Claims. (Cl. 208—88)

The present invention relates to a process for the removal of heavy metals or compounds thereof, such as heavy metal oxides, from hydrocarbon stocks and more particularly to a process for the removal of relatively small amounts of heavy metals or their compounds from petroleum and other hydrocarbon feed stocks which are to be subjected to catalytic conversion operations, such as cracking, reforming, dehydrogenation, and the like.

It is well known that many hydrocarbon feed stocks contain appreciable amounts of heavy metals or compounds thereof, such as lead, iron, nickel and copper or their compounds. It is also known that such heavy metals or metal compounds are liable to deteriorate the activity of and even to poison certain types of catalysts, when such metal-containing feed stocks are subjected to a treatment in the presence of such types of catalysts. Thus, cracking catalysts, such as silica-alumina catalysts alone or in admixture with other metal oxides suitable for this purpose, are deteriorated or poisoned by heavy metals, such as vanadium, iron, nickel and copper, and dehydrogenation catalysts of the group of platinum and palladium metals are poisoned by lead, tin, arsenic, mercury and the like.

It is an object of the present invention to prevent the deterioration and poisoning of hydrocarbon conversion catalysts by removal of heavy metals and their compounds from hydrocarbon feed stocks containing them.

It is another object of the present invention to remove heavy metals and their compounds from hydrocarbon stocks containing the same, in a simple and economical manner.

It is a further object of the present invention to remove from hydrocarbon conversion stocks such heavy metals as lead, iron, nickel and copper and compounds thereof which are capable of deteriorating and poisoning hydrocarbon conversion catalysts.

Other objects and advantages of the present invention will be apparent from the subsequent description and the claims.

It has been found that heavy metals, such as, for instance, lead, iron, nickel, and copper and certain compounds thereof, may easily and substantially completely be removed from hydrocarbons and hydrocarbon mixtures, particularly from hydrocarbon feed stocks to be subjected to catalytic treatment, by subjecting these hydrocarbons or hydrocarbon mixtures containing such heavy metals to a treatment with elementary sulfur, thereby forming sulfides of the heavy metals, which sulfides are insoluble in the hydrocarbons under treatment.

Various methods may be used for this treatment of hydrocarbon feed stocks containing heavy metals with elementary sulfur.

One of these methods consists in passing the heavy metal-containing feed stocks in the liquid or gaseous state through a bed of solid, powdered or granular elemental sulfur, preferably at a temperature between room temperature and about 30° F. In order to minimize the

solubility of the sulfur in heavy feed stocks, we prefer to use solid sulfur of especially low solubility, that is, sulfur m_{μ} , conveniently designated as "S μ ," obtained by rapid cooling either of sulfur vapor or of liquid sulfur heated to 450–550° F.

Another method of the treatment of the hydrocarbon feed stocks containing heavy metals, or the like, with elementary sulfur consists in scrubbing these feed stocks with liquid sulfur, preferably in the temperature range of about 250–320° F. As liquid sulfur has a low, almost constant viscosity (of about 10 centipoises) in this temperature range, while its vapor pressure is very low (about 0.37 mm. Hg. at 320° F.), the treatment in this temperature range is particularly simple and convenient.

15 Other methods for the treatment of hydrocarbons and hydrocarbon mixtures with elementary sulfur in order to remove heavy metals and metal compounds from such hydrocarbons and hydrocarbon mixtures can also be employed within the scope of the present invention.

20 Any relatively small amount of sulfur which might be introduced by the treatment according to the present invention into the hydrocarbon feed stock, or the like, will not injure cracking catalysts free of iron, nickel, copper, or the like, or dehydrogenation metal catalysts, 25 such as platinum or palladium.

One and the same batch of elemental sulfur may be used in any of these methods for the treatment of a very large amount of hydrocarbons, particularly since the percentage of heavy metals contained therein generally 30 will be small. If and when desired, however, the sulfur employed may be freed from the metal sulfides formed and accumulated therein by any suitable method, such as by a filtration of the liquefied sulfur, or by an extraction of the sulfur by a volatile organic solvent such 35 as carbon disulfide.

Example I

A hydrocarbon feed stock to be used in catalytic conversion processes and containing relatively small, but 40 appreciable amounts of such heavy metals as lead, iron, nickel and/or copper is continuously passed in the liquid state at a temperature of about 100° F. through a bed of solid powdered sulfur (S μ "). The heavy metals are retained in the sulfur bed and thus removed by this treatment from the hydrocarbon stock. Treatment at temperatures up to about 210° F. is likewise effective.

Example II

A naphtha stock, having an initial boiling point of 163° F. and an end point of 214° F., containing heavy metals including 2 parts per million (p. p. m.) of lead was 50 treated with 0.1% flowers of sulfur at room temperature. This stock was filtered after the treatment and was found to contain less than 0.5 p. p. m. of lead.

Example III

Another sample of the same naphtha used in Example II was treated with 0.01% solid sulfur and then distilled. The distillate tested free of lead.

Example IV

Hydrocarbon mixtures containing heavy metals, such as lead, nickel, copper and the like or compounds thereof, either separately or in mixture, are introduced into a scrubber containing liquid elementary sulfur and maintained at a temperature of about 285° F. The heavy metals and metal compounds are retained in the sulfur by the formation of insoluble sulfides of said metals and are thus removed from the hydrocarbon mixtures.

Under certain conditions it is also possible to treat hydrocarbon feed stocks containing heavy metals with sulfur vapor and thereby to remove the heavy metals

from the hydrocarbons under treatment which can be separated from the sulfur by condensing the sulfur vapors.

If any sulfur is incorporated into the treated hydrocarbons and it is desired to remove such sulfur from these hydrocarbons before further treating them, this may be done by any of the usual and known methods for the removal of relatively small amounts of sulfur from hydrocarbons. Generally, however, the small amounts of sulfur which might be incorporated into the hydrocarbons by the treatment described will not be disadvantageous in further treatment of the hydrocarbons, particularly in catalytic conversion operations, and will not injure cracking catalysts free of iron, nickel or the like, or platinum metal dehydrogenation catalysts.

Obviously many modifications and variations of the invention as hereinbefore set forth may be made without departing from the spirit and scope thereof and therefore only such limitations should be imposed as are indicated in the appended claims.

This application is a continuation of application Serial No. 267,307, filed January 19, 1952, now abandoned.

What is claimed is:

1. The process of converting liquid hydrocarbon feed stock containing relatively small amounts of heavy metals which includes the steps of subjecting said hydrocarbon feed stock to the action of elementary sulfur to bring about the formation of heavy metal sulfides, separating a fraction having a reduced content of heavy metals and heavy metal sulfides, said fraction containing substan-

5 tially all of said hydrocarbon feed stock, and thereafter subjecting the thus metal-free hydrocarbon to a conversion treatment in the presence of a catalyst readily poisoned by heavy metals, said catalytic conversion treatment being at an elevated temperature.

2. The method of claim 1 in which the elementary sulfur is in the S_2 form.

10 3. In the process of catalytically cracking petroleum fractions derived from crude oils containing heavy metal components deleterious in the catalytic cracking of such oils, the improvement which comprises subjecting an oil containing such heavy metal components to contact with elementary sulfur, reacting said sulfur with said components and forming insoluble heavy metal sulfides, and removing said heavy metal sulfides and excess sulfiding agent from the oil prior to contact of the oil with the cracking catalyst.

UNITED STATES PATENT OFFICE

Certificate of Correction

Patent No. 2,854,399

September 30, 1958

Sol W. Weller

It is hereby certified that error appears in the printed specification of the above numbered patent requiring correction and that the said Letters Patent should read as corrected below.

Column 1, line 72, for "30° F." read $230^{\circ} F.$; column 2, line 3, for "sulfur $m\mu$ " read *sulfur mu*.

Signed and sealed this 24th day of February 1959.
